[57] **CLAIM**

The ornamental design for a ball return and storage rack, as shown and described.

DESCRIPTION

FIG. 1 is a perspective view of a bowling ball return and storage rack in accordance with the present invention; FIG. 2 is a side-elevational view of the ball return and storage rack as shown in FIG. 1, and which is a mirror image of the opposite side;

FIG. 3 is a side-elevational view taken from one end of the ball return and storage rack shown in FIGS. 1 and 2; FIG. 4 is a top or plan view of the ball return and storage rack shown in FIGS. 1-3;

FIG. 5 is a bottom plan view of the ball return and storage rack shown in FIGS. 1-4; and,

FIG. 6 is a side-elevational view taken from an opposite end of the ball return and storage rack shown in FIG. 3.
